CLAIM

We claim the ornamental design for a kinetic magazine loader, as shown and described.

DESCRIPTION

FIG. 1 is a front, right, top perspective view of a kinetic magazine loader showing our new design;
FIG. 2 is a rear, left side, top perspective view thereof;
FIG. 3 is a front, right, top perspective view of; and,
FIG. 4 is a rear, left side, top perspective view thereof.
The bottom of the kinetic magazine loader is not shown in the drawing and forms no part of the claimed design.
Broken lines shown in the drawings illustrate structure or features which form no part of the claimed design.
